UNITED STATES PATENT OFFICE.

JOHN NATHAN, OF LOS ANGELES, CALIFORNIA.

GARMENT-PRESS.

1,202,304.

Specification of Letters Patent.

Patented Oct. 24, 1916.

Application filed August 28, 1915. Serial No. 47,855.

To all whom it may concern:

Be it known that I, JOHN NATHAN, a subject of Great Britain, residing at Los Angeles, in the county of Los Angeles and State of California, have invented a certain new and useful Garment-Press, of which the following is a specification.

My invention relates to a press for clothes, and particularly for trousers, and has for one of its objects to provide a simple, light, strong and portable device which may be folded into a compact shape and which will neatly press the article and effectively remove the bag and other distortions of the garment.

Another object of my invention is to provide a press in which the garment will not creep when the press is folded.

These and other objects are attained by the device described in the subjoined specification and represented in the accompanying drawing; in which—

Figure 1 is a plan view of the press in open position. Fig. 2 is a plan view showing the press folded after the placement of trousers therein. Fig. 3 is a plan view showing the press folded for packing in a suitcase or other carrier. Fig. 4, is a plan view showing the two-part member and the flexible joining means therefor. Fig. 5 is a side view. Fig. 6 is a side view of the press folded, and Fig. 7 is a plan view showing the two-part member in separated position and the joining means therefor.

With special reference to the drawing, my invention consists of a single blank or strip of material having an outline tapering from the extremities to the center thereof and bendable centrally upon itself to form two members 1 and 2, hingedly connected, each partaking of the shape of a garment, in the instance trousers. The member 1 is scored approximately centrally of its length, as at 3, to enable same to be folded upon itself.

The member 2, is made in two parts, the disjoined part 4, being secured to its complementary part by a flexible strip 5, pasted or otherwise fastened thereto, whereby such disjoined part may be moved relatively to the complementary part. When in use the edge of the disjoined part is moved in contact with the edge of the complementary

part, causing thereby the flexible strip 5 to bow above the plane of the member 2, as seen in Figs. 4 and 5. The members 1 and 2, with the garment therebetween are held together by suitable fastening devices, such as clips 6. When the press, with the trousers therein, is folded in the manner shown in Fig. 3, the flexible strip takes the contour of the fold, while the disjoined part 4, remains in its adjusted or normal position, hence creeping of the cloth of the garment and consequent distortion is avoided. The strip is provided with a central slot 7, parallel with the line of bend thereof, through which the bottom or cuffs of the trousers may be extended, where the crease or press is not desired at that point, and to insure strength at the bend and adjacent the slot, suitable reinforces 8 may be provided.

As shown in Figs. 1 and 4, the member 1 may be provided with side flaps or wings 9 and 10, which extend from each end preferably to the center and in line with the score 3 of such member, these flaps or wings serving to reinforce and preserve the member 1 against warping. In practice they are arranged to be folded over the member 2, as shown in Fig. 4.

What I claim is:

1. A trousers press consisting of a single strip of material tapering from the extremities to the center thereof and bendable upon itself to form two members, one of said members being scored, and the other member consisting of two parts, and a flexible means for securing said parts together.

2. A trousers press consisting of a single strip of material tapering from its extremities to the center thereof and forming two members hingedly connected, one of said members having centrally thereof a score, and the other member consisting of two parts, and a flexible strip for securing the disjoined part to its complementary part.

3. A trousers press consisting of two members hingedly connected and provided with a slot in line with the hinged connection, one of said members consisting of two parts flexibly connected.

4. A trousers press consisting of two members hingedly connected and provided with a slot in line with the hinged connec-

tion, reinforces adjacent said slot, one of said members consisting of two parts flexibly connected, and means to hold said members together.

5. A trousers press consisting of two members hingedly connected, one of said members having side flaps arranged to overlap the other member when folded, and

such other member consisting of two parts flexibly connected.

In testimony whereof I affix my signature in the presence of two witnesses.

JOHN NATHAN.
